UNITED STATES PATENT OFFICE.

HENRY F. LOOMIS, OF READING, PENNSYLVANIA.

PROJECTILE.

1,247,430.

Specification of Letters Patent. Patented Nov. 20, 1917.

Application filed March 1, 1916. Serial No. 81,522.

To all whom it may concern:

Be it known that I, HENRY F. LOOMIS, a citizen of the United States, residing at Reading, in the county of Berks and State of Pennsylvania, have invented certain new and useful Improvements in Projectiles, of which the following is a specification.

My invention relates particularly to explosive projectiles adapted for use in trench warfare or for like purposes, and my main object is to provide for securing the maximum destructive effect upon trench structures adjacent the point of impact with the ground.

Ordinarily the maximum effect has not been produced because of the undue penetration of the earth occurring before explosion of the charge; and my invention consists in an improved construction of the nose portion of the projectile whereby such excessive penetration will be prevented, while at the same time the axial line of the projectile will be held true to its line of flight as heretofore.

Figure 1 is an elevation of a shell embodying my invention in preferred form.

Fig. 2 is a longitudinal section of the same.

In the specific form shown in the drawing *a* represents a cylindrical shell of ordinary form having an explosive chamber *b* formed by a partition wall *c* screwed into the open forward end thereof; and *d* represents a detonating device in the form of an adjustable fuse secured in the partition *c* and extending into the charge chamber *b* to explode the charge contained therein at a predetermined time.

In order to secure the most effective results from such explosive shells especially when directed against entrenchments, the modern practice has been to set the fuse to explode the charge only after the shell has struck and penetrated the earth; and the best results are attained when the explosion occurs after penetrating the earth to a depth not very much exceeding that of the depth of the trench against which it is directed. The force with which the ordinary shell strikes the earth, particularly when dis-

charged at the great elevation commonly practised, causes it to penetrate to a great depth, and the force of the explosion which is effective in destroying the trench is greatly reduced. It is practically impossible to so time the fuse as to explode the shell during its penetrative movement, and I therefore provide for so forming the shell that it will travel through the air with a normal trajectory, but upon impact with the earth will be subjected to a retarding effect adapted to reduce its penetration and cause the shell to come to rest at a point not greatly below the bottom of an adjacent trench. To this end I provide the shell with a nose portion in the form of a hollow-cone frustum; the specific nose portion *e* illustrated in the drawing being screwed into the shell at *f*, and so shaped exteriorly as to provide it with a modified conoidal end such as is found to be desirable for maintaining true flight, though hollowed out so as to retard penetration. The usual pointed end of this hollow nose piece *e* is cut away to form an opening *h* to the hollowed-out chamber *i*. This opening *h* is large enough to admit the passage of the time setting tool for the fuse; and holes or slots *k* may be provided in the walls of the hollowed nose, arranged spirally or otherwise, as desired.

When discharged from the gun the conoidal nose *e* will maintain axial alinement during the flight of the shell, the inrush of air through the opening *h* escaping through the holes *k*. Upon striking the earth the opening *h* will admit earth to the chamber *i*, which will flow through the holes *k* under the pressure, thus very effectively retarding penetration of the projectile.

My improved shell with its hollow retarding nose will permit timing the explosion of its charge so as to secure the most effective results, and shells will have effective results equal to or greater than much larger and highly explosive ones operating as heretofore, inasmuch as they will explode at a proper depth relative to the trench instead of a depth greatly below it. My improved nose construction may obviously be formed integral with the shell body, and be readily

modified in form within the limits of my invention as defined in the claim.

What I claim is:

An explosive projectile comprising a cylindrical shell, a separately formed end-closure therefor provided with a detonating device having an adjustable charge-exploding

10
fuse, and a separately formed nose portion in the form of a hollow-cone frustum having a front opening smaller than said end-closure and walls of substantially uniform thickness provided with apertures.

In testimony whereof I affix my signature.

HENRY F. LOOMIS.
